(57) **CLAIM**

The ornamental design for a protective cover for an input device, as shown and described.

DESCRIPTION

FIG. 1 is a perspective view of our protective cover for an input device showing our new design;

FIG. 2 is a second perspective view thereof;

FIG. 3 is a third perspective cut away and magnified view thereof taken from line 3-3 on FIG. 1;

FIG. 4 is a top plan view thereof;

FIG. 5 is a bottom plan view thereof;

FIG. 6 is a rear elevational view thereof;

FIG. 7 is a front elevational view thereof;

FIG. 8 is a left side elevational view thereof; and

FIG. 9 is a right side elevational view thereof.

FIG. 10 is a perspective view of second embodiment of our protective cover for an input device showing our new design; and,

FIG. 11 is a second perspective view thereof.

Broken lines represent environment and form no part of the claim.

1 Claim, 8 Drawing Sheets
